L. K. O. BAKKE

TRIPPING MECHANISM FOR BINDERS

Filed Sept. 24. 1924

Inventor
L. K. O. Bakke

Fig. 6. by Bair & Freeman Atlys.

UNITED STATES PATENT OFFICE.

LAURITS KRISTIAN OLESEN BAKKE, OF EMMETSBURG, IOWA.

TRIPPING MECHANISM FOR BINDERS.

Application filed September 24, 1924. Serial No. 739,742.

The object of my invention is to provide a tripping mechanism for binders of simple, durable and comparatively inexpensive construction.

5 More particularly, my invention relates to an attachment adapted to be secured to the seat supporting pipe of a binder and operatively connected with the bundle carrier trip rod, whereby the attachment may be operated when desired for mechanically operating the bundle carrier of a binder.

10 Still a further object is to provide a bell crank lever member adapted, when a foot lever is operated, to release the tripping mechanism for allowing the same to be operated from one of the moving parts of the binder itself.

15 My present invention is an improvement over my patent on a carrier operating mechanism for binders No. 1,502,102, issued July 22, 1924.

20 With these and other objects in view, my invention consists in the construction arrangement and combination of the various parts of my device, whereby the objects contemplated are attained, as hereinafter more fully set forth, pointed out in my claims, and illustrated in the accompanying drawings, in which:

25 Figure 1 is a side elevation of a seat supporting pipe of a binder with my improved tripping mechanism for the bundle carrier thereof attached to the seat supporting pipe.

30 Figure 2 is a vertical sectional view taken on line 2—2 of Figure 1.

35 Figure 3 is a top, plan view of the grain shield support, which is secured to the frame of my attachment.

40 Figure 4 is a detail, sectional view taken on line 4—4 of Figure 1 showing the connection between a moving part of the binder and my attachment.

45 Figure 5 is a detail, sectional view taken on line 5—5 of Figure 1; and

50 Figure 6 is a detail view showing one of the drive shafts and the gear mounted thereon.

55 In the accompanying drawings, I have used the reference numeral 10 to indicate generally a seat supporting pipe of a binder.

The ordinary binder includes a grain elevator 11 operated from a shaft 12 journalled in the frame 13 of the binder. In some types of binders the shaft 12 has a combined gear and sprocket 14 thereon which

are driven from the traction wheels of the binder for imparting rotation to the shaft 12 and the grain conveyor 11.

My tripping mechanism is designed to be driven from the shaft 12 and I provide 60 a pulley wheel 15 connected to a plate or the like 16, which is bolted to the spokes of the sprocket 14 by U-bolts 17^a.

The pulley wheel 15 is provided with a flanged bead 17 for retaining the belt 18 65 in place. The belt 18 is used for driving my bundle carrier tripping mechanism, as will hereinafter be more fully described.

70 My attachment includes a frame 19 in the form of a casting. The frame 19 is connected to the seat supporting pipe 10 at its forward end by a U-bolt 20. The frame 19 has an outwardly extending flange 21 formed on one side, which is provided with a notch 22 having tapered sides for receiving 75 the seat supporting pipe 10, as clearly shown in Figure 2 of the drawings.

75 The rear end of the frame 19 has a slot 23 which receives a bolt 24 therethrough for retaining the rear end of the frame to the 80 seat supporting pipe 10. The bolt 24 is ordinarily used for securing a foot rest to the seat supporting pipe whereby the driver of the binder may step upon the same in order to get the seat of the binder.

85 The ordinary foot rest is removed when my attachment is secured to the binder, and in order to have a foot rest, I form the frame 19 with an enlarged foot rest portion 25, which is shown in Figure 3 of the drawings.

90 The slot 23 permits the frame 19 to be secured to a seat supporting pipe 10 of different sizes, the slot 23 compensating for any slight variations.

95 The frame 19 has a pair of outwardly extending spaced ears 26 to which are pivotally connected lugs 27 which have the grain shield support 28 mounted therebetween which is ordinarily secured to the seat supporting pipe 10, and when my attachment 100 is used, I mount the grain shield support thereon.

105 The grain shield support 28 has an ordinary grain shield pivot bolt 29 therein.

28 Adjustment of the grain shield support 105 may be accomplished by positioning of the adjuster rod 30 in any of the openings 31 formed in the enlarged portion 25 of the frame 19.

110 The adjuster rod 30 is pivotally connected

to a plate 32 secured to the outer free end of the grain shield support 28, all as clearly shown in Figure 3 of the drawings.

The frame 19 has a pair of spaced bearings 33 formed thereon in which are mounted a stub shaft 34. One end of the stub shaft 34 has a pulley wheel 35 fixed thereto, around which the belt 18 extends. The belt 18 drives the shaft 34.

10. Fixed to the shaft 34 and spaced between the bearings 33 is a gear 36.

The frame 19 also has a bearing 37 in which is mounted a shaft 38.

15. A mutilated bevel gear 39 is keyed to the shaft 38 and is adapted to mesh with the bevel pinion or gear 36. The bevel gear 39, which has been referred to as a mutilated gear, has a number of teeth missing therefrom so as to provide a blank space 40, 20. shown in Figure 2 of the drawings.

The normal position of the bevel gear 39 is such that the bevel pinion or gear 36 is partially received within the blank space 40.

25. On the back side of the gear 39 is formed an extension or catch lug 41.

A bell crank lever 42 is pivotally connected to the frame 19 by means of the bolt 43. One part of the bell crank lever 42 is 30. provided with a hook 44 adapted to coact with the extension 41 for retaining the gear 39 against rotating movement.

35. A roller 45 is also mounted on the gear 39 and is adapted to be struck by the portion 42^a of the lever 42 when the lever 42 is moved, as will hereinafter be more fully set forth.

40. The lever 42 has fixed to it a downwardly extending arm 46. A link 47 is pivotally connected to the lower end of the arm 46 and extends forwardly therefrom and has its forward end connected to a bell crank lever 48 mounted in a bearing 49.

45. One side of the bell crank lever 48 has a foot pedal 50 thereon.

The seat 51 rests upon a seat stand 52, which is fastened to the supporting pipe 10.

50. The bell crank 48 is adapted to be operated by the foot of the driver or by the pull of a rope in case the binder is being pulled by a tractor, in a direction indicated by the arrow 52^a for causing the link 47 to operate also in the direction indicated by the arrow 52^a.

55. The forward movement of the link 47 will cause the bell crank lever 42 to swing upon its pivot to the position shown in dotted lines in Figure 1 of the drawings for releasing the hook 44 from the extension 41 and at the same time, the portion 42^a will strike the roller 45 for causing the gear 39 to commence to rotate.

60. The gear 39, when started by being engaged with the portion 42^a, will mesh with the bevel pinion 36, thereby insuring the

gear 39 to be rotated one complete revolution from power supplied from a moving part of the binder itself.

The ordinary binder is provided with a bundle trip rod 53, which is ordinarily operated manually and in order to cause the bundle trip rod to operate from the gear 39, I insert one end of the rod 53 into a socket 54 and lock it therein by means of the set screws 55.

75. The sockets 54 is pivotally connected to the gear 39 through the bolt 56. The bolt 56 is mounted at a point spaced away from the shaft 38 and rotates in the path of a circle with the shaft 38 as its axis.

80. From the construction of the parts just described, it will be seen that each time the gear 39 is permitted to rotate, it will cause the bundle carrier trip rod 53 to be operated for operating the bundle carrier, which forms a part of the binder itself.

85. In order to prevent the gear 39 from any possible backward movement, I mount a pawl 57 on the frame 19 and place a coil spring 58 on a bolt 59 between the frame 19 and the pawl 57. The pawl 57 rests against the underside of the extension 41 and prevents any rearward or backward rotation of the gear 39.

90. The bolt 59 limits the movement of the pawl 57 in one direction.

95. In order to insure the hook 44 to engage the extension 41, I connect a coil spring 60 to the lower end of the arm 46 and to an arm 61 on the frame 19.

100. The spring 60 is connected to the arm 46 through the medium of a rod 62 which extends through the arm 46, as clearly shown in Figure 5 of the drawings.

105. The rod 62 is screw threaded, as at 63, and is slidably mounted within an opening (not shown) formed in the arm 61 of the frame 19.

110. In order to limit the amount of swinging movement of the bell crank lever 42 in either direction, I provide a pair of stops 64 and 65 on the rod 62 on each side of the arm 61.

115. The stops 64 retain the bell crank lever 42 at one limit of its movement and the stops 65 limit the amount of movement of the bell crank lever 42 in the opposite direction.

120. When the gear 39 has been operated, it will cause the roller 45 to strike against the curved surface of the portion 42^a and will ride thereover.

125. The spring 60 will cause the hook member 44 of the bell crank lever 42 to be in its solid line position, as shown in Figure 1, where it will be in position to engage the extension 41 or catch 41.

130. It will be seen from the foregoing that the gear 39 may be put into motion by simply pushing the foot piece 50 of the bell crank lever 48 in the direction indicated by the arrow 52^a.

The bell crank lever 42 insures the releasing of the catch or extension 41, and at the same time causes the gear 39 to be positively engaged for starting it so that it meshes with 5 the bevel pinion 36 and thereafter a complete revolution is had for moving the bundle carrier trip rod 53 as necessary.

My attachment is very simple and can be quickly and easily connected to a binder and 10 furnishes the necessary mechanism for operating and tripping the bundle carrier of the binder.

A guard 66 is secured to the frame 19 and extends over the gear 39.

15 Some changes may be made in the construction and arrangement of the various parts of my invention, without departing from the real spirit and purpose of my invention and its my intention to cover by 20 my claims, any modified forms of structure or use of mechanical equivalents, which may be reasonably included within their scope.

I claim as my invention:

25 1. A bundle carrier tripping mechanism for binders comprising a frame mounted on the binder, a gear on said frame operatively driven from a moving part of the binder, a mutilated gear arranged adjacent 30 said first gear and adapted to be operated therefrom, a roller on said mutilated gear, a bell crank lever on said frame having a hook member on one end for engaging said mutilated gear and retaining it in inoperative 35 position, the other end of said bell crank lever terminating adjacent said roller whereby disengagement of the hook end thereof from the mutilated gear will cause the other end of said lever to strike against 40 said roller, thereby causing said gear to start to rotate and a pitman connected to said mutilated gear for tripping the bundle carrier.

2. A binder bundle carrier tripping mechanism comprising a frame mounted on the binder, a continuously operated gear on said frame, a mutilated gear arranged adjacent said first gear and adapted to be operated therefrom, a lever on said frame having 45 a hook member for engaging said mutilated gear to retain it in inoperative position, a cam portion on said lever adjacent said mutilated gear and designed to strike a roller on the mutilated gear upon disengagement of the hook end and the gear whereby

said mutilated gear is started to rotate, yielding means for causing said lever to engage said mutilated gear manually operated means for causing disengagement thereof, a pitman connecting said mutilated 60 gear to the bundle carrier whereby rotation of the mutilated gear will trip said carrier.

3. A bundle carrier tripping mechanism for binders comprising a frame mounted on the binder, a continuously rotating means 65 on said frame, a second means rotatably arranged adjacent said first means and adapted to be operated thereby, a projection and a roller mounted on said second means, a bell crank lever on said frame having 70 a hook member on one end for engaging one side of said projection and retaining said second means in inoperative position, a spring actuated pawl mounted on said frame for engaging the other side of said projection to prevent reverse rotation of said second means, the other end of the bell crank lever terminating adjacent said roller whereby movement of said bell crank lever to position where the hook end thereof will disengage said projection and cause the other end thereof to strike against said roller causing said second means to be engaged by 75 said first means and means for connecting said second means to the bundle carrier of 80 the binder whereby said bundle carrier will be dumped and returned each time said second means is rotated one complete rotation.

4. A bundle carrier tripping mechanism 90 adapted to replace the foot trip comprising a frame mounted on the binder, means on said frame operatively driven from a moving part of the binder, a second means adjacent 95 said first means adapted to be operated therefrom, a projection and a roller thereon, a lever resiliently held in engagement with said projection to prevent the rotation of said second means in one direction, a spring 100 actuated pawl for preventing rotation of said second means in the opposite direction, a cam surface on said lever adjacent said roller for striking said roller when said lever is disengaged from said projection, against the resiliency of the lever, said cam surface 105 serving to move said lever by being struck by said roller when said lever is maintained in projection disengaging position.

LARUTS KRISTIAN OLESEN BAKKE.
